Primary Examiner — L. A. Grabenstetter

(57) **CLAIM**

The ornamental design for a mobile phone case, as shown and described.

DESCRIPTION

FIG. 1 is a front view of the mobile phone case showing my new design, shown in a first configuration;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a second front view thereof, shown in a second configuration; and,

FIG. 8 is a third front view thereof, shown in a third configuration.

The broken lines in FIG. 6 show portions of the mobile phone case which form no part of the claimed design.

1 Claim, 8 Drawing Sheets
